UNITED STATES PATENT OFFICE.

CARL HEAD, OF DECATUR, ILLINOIS.

INDOOR-FOOTBALL GAME.

Application filed April 12, 1922. Serial No. 551,911.

To all whom it may concern:

Be it known that I, CARL HEAD, a citizen of the United States, residing at Decatur, in the county of Macon and State of Illinois, have invented new and useful Improvements in Indoor-Football Games, of which the following is a specification.

This invention relates to amusement devices, particularly to games, and has for its object the provision of a game designed to be played upon a playing board for carrying out the action of the ordinary football game, the same requirements applying as in the outdoor game and the same series of plays with the resultant advantage and penalties being also used.

An important object is the provision of a game of this character in which use is made of some counting means such as a pair of differently colored dice, a spinning pointer movable over a graduated dial, or a spinning disk cooperating with a fixed pointer, the number obtained from the use of whatever counting device is used referring to a series of numbers on a chart which bears the names of the various plays together with the advantages and penalties.

Another object is the provision of a game of this character which includes a board which may be subdivided by marks inscribed thereon to define a football playing field or which may be provided with a plurality of holes into which may be inserted the markers indicating the location of the ball and the linesman along the field.

Another object is the provision of a game of this character which not only constitutes an amusement device but which is also highly advantageous as means for instructing new players on school teams and the like as to the possible plays and the results thereof.

An additional object is the provision of a device of this character which will be simple and inexpensive in manufacture easy to use, entertaining and instructive and a general improvement in the art.

With the above and other objects and advantages in view, the invention consists in the details of construction to be hereinafter more fully described and claimed, and illustrated in the accompanying drawings, in which:

Figure 1 is a perspective view of the game board used in carrying out my game,

Figure 2 is a detail sectional view therethrough,

Figure 3 is a perspective view of a pair of dice used as counters and showing the manner of counting,

Figure 4 is a plan view of a rotary pointer co-operating with a graduated scale,

Figure 5 is a similar view showing a rotary disk co-operating with a fixed pointer and

Figure 6 is a fragmentary plan view of the board showing a modified form of construction.

Referring more particularly to the drawings the numeral 10 designates a game board which is preferably rectangular in shape and elongated but which may be constructed of any suitable material such as wood, card board or the like, painted or otherwise treated to have an attractive appearance. 70 This board has a playing surface 11 designed for representing a football field and this surface is marked off with the end zones indicated at 12, the goal lines indicated at 13 and also with subdivisions representing the yard lines in conformity to the marking of a football field. As shown in Figure 1 and also in Figure 2 these subdivisions are holes 14 into which may be inserted markers 15 and 16 designating the location of the ball and the linesman, the marker 15 being preferably provided with a head representing a football so as to avoid any confusion as to the identity of the two markers, the marker 16 having a head of 80 some arbitrary formation which will contrast with the marker 15. If preferred, as shown in Figure 6 the subdivisions of the playing surface may be merely lines 17 inscribed or painted upon the board at the 85 proper distances apart. In this modification the markers 15 and 16 might be replaced with other markers 18 and 19 which would be merely laid upon the board instead of being inserted within holes like the markers 15 and 16.

Used in connection with the game board is a chart which is preferably printed or otherwise inscribed upon the board at the sides thereof, though it might be formed as 105 a separate sheet for use in conjunction with the board. This chart is designated by the numeral 20 and will be divided into two sections as shown in Figure 1 for convenience and for making the playing surface 110

have a more uniform appearance. This chart consists of a plurality of vertical columns 21 at the tops of which are the headings "End run," "Punt," "Line buck" and "Forward pass," the various legends designating the various types of plays in a football game. Each column 21 is subdivided into spaces 22 within which are inscribed the advantages gained by certain plays and penalties resulting from different causes, the arrangement of the inscriptions being of course arbitrary but being such that they will truly represent the occurrences in a regular game of football. Between the pairs of columns 21 are columns 23 within which are inscribed, opposite the spaces 22, numbers which are here shown as ranging from 11 to 66 though it should be understood that this definite arrangement is also arbitrary depending upon the type of means employed in the carrying out of the game for ascertaining to what number the successive players are entitled.

In playing the game I may prefer to make use of a pair of dice shown in Figure 3, these dice being each inscribed with spots ranging from 1 to 6 and being each of a different color, red and green being illustrated in this instance, the purpose of the difference in color being that the die of one color should be read before the die of the other color as it is intended that the spots displayed when the dice are thrown should not be added as in crap and other games, but should be read in their multiple relation, as for instance the dice shown in Figure 3 are turned up to read "35." In other words one die represents units and the other tens.

Instead of using the pair of dice I may use a spinner as shown in Figure 4, this spinner including a stationary dial or disk 24 over which may be spun a pivoted arrow 25 the dial having a series of numbers on its face corresponding to the numbers in the columns 23 on the game board. Another variation is that I may make use of the spinner shown in Figure 5, in which instance I provide a base member 26 upon which is pivoted a rotatable dial 27 which is graduated and which co-operates with a fixed pointer 28 on the base.

In starting of the game the marker 15, or 18 as the case may be, is placed at the proper place on the field corresponding to the position of the ball indicated by the initial spin or throw of the dice in making the kick off. The other markers 16 or 19 as the case may be is placed at a point ten yards ahead of the markers 15 or 18 to indicate the distance to be made in four downs. The players then either throw dice or operate whichever spinner is used in order to secure a number which will entitle the player to a certain play with its consequent advantages or penalties. When making a play

the player must first call for the play he intends to make, that is either "End run," "Punt," "Line buck" or "Forward pass" prior to his throwing of the dice or operation of the spinner. When the player then obtains a number he reads down the column 23 until he reaches the number he has made and then refers across to the corresponding space 22 in the proper one of the columns 21 having a heading corresponding to the play he called. The space corresponding with the number thrown or spun will inform the player as to what advantage or penalty he receives as the result of his play. The player then moves the marker representing the ball correspondingly upon the playing surface. This is continued until the game has been played in a full and complete manner corresponding to the playing of a regular football game.

The device is not only capable of use as an amusement apparatus but is also advantageous in instructing new players on the teams of schools, colleges and the like as it will acquaint them with the possible plays, the possible penalties and advantages and will also inform them as to the different points along the field from which it is permitted to attempt to try a drop or placement kick, the distance being of course arbitrary, and being agreed upon in advance.

From the foregoing description and a study of the drawings it will be apparent that I have thus provided a game which will be highly amusing, entertaining and also instructive, which will have the additional advantage of being easy to play and count. Owing to the simplicity and the fewness of the parts it is apparent that the cost of manufacturing the device should be slight and owing to the particular arrangement and construction it will be seen that there is nothing at all to get out of order, this being a very important advantage as will be readily apparent, to those who have endeavored to manipulate some of the complicated game devices in use.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim:

1. A game device comprising a game board having a playing surface designed to represent a football field, the surface being marked to represent the points forming or constituting the successive stations and playing points of a football game, in combination with movable markers designed to be placed upon the playing points and moved in conformity with possible plays

- of a football game, a guide chart on the board at opposite sides of the playing surface, bearing the names of the different plays together with indicia as to penalties and advantages corresponding with a series of numbers, and means operable by the players for obtaining certain numbers.
2. A game device comprising a game board having a playing surface designed to represent a football field, the surface being marked to represent the points forming or constituting the successive stations and playing points of a football game, in combination with movable markers designed to be placed upon the playing points and moved in conformity with possible plays of a football game, a guide chart provided directly upon the board at opposite sides of the playing surface including columns having headings corresponding to the possible plays, said columns being subdivided into spaces bearing indicia as to penalties, together with distances pertaining thereto, advantages, the columns being furthermore inscribed opposite said spaces with a series of numbers, and means operable by the players for obtaining a number corresponding to the numbers on the chart, said means including dice of different colors intended to be read in their multiple relation, one indicating units and the other tens.

In testimony whereof I affix my signature.

CARL HEAD.
